(57) **CLAIM**

The ornamental design for a chain for a rock guitarist, as shown and described.

DESCRIPTION

FIG. 1 is a front perspective of the chain for a rock guitarist in an environmental view;

FIG. 2 is a front perspective of a single-strand embodiment of the chain;

FIG. 3 is a front perspective of double-strand embodiment of the chain;

FIG. 4 is a front perspective of a triple-strand embodiment of the chain; and,

FIG. 5 is a front perspective of a quadruple-strand embodiment of the chain.

The broken line in FIG. 1 depicting a rock guitarist is for illustrative purposes only and forms no part of the claimed design.

The chain strands in FIGS. 2-5 are understood to be continuous throughout the entire length of the chain, with brackets indicating, for ease of illustration, that the precise length of each chain strand is not claimed and that chain strands may have the same or different length.
